(57) **CLAIM**

The ornamental design for a camera recording device for use with a shoulder strap, as shown and described.

DESCRIPTION

FIG. 1 is a front, top and right side perspective view of a camera recording device for use with a shoulder strap showing my new design;

FIG. 2 is a rear, bottom and left side perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a right side elevational view thereof;

FIG. 8 is a left side elevational view thereof;

FIG. 9 is a reduced front, top and right side perspective view of the camera recording device in use with a shoulder strap; and,

FIG. 10 is a reduced front elevational view of the camera recording device in use with a shoulder strap.

The broken lines in FIGS. 9 and 10 depicting a shoulder strap and human figure are shown to illustrate environment only and form no part of the claimed design.
